Switch tongue, a novel paved track switch, and connecting means therefor.

This invention relates to railway switches and more particularly to a novel paved track switch where an open switch is not permitted.

UNITED STATES PATENT OFFICE

2,607,003

RAILWAY SWITCH

Eugene O. Humphrey, Salt Lake City, Utah

Application September 21, 1949, Serial No. 116,889

5 Claims. (Cl. 246—435)

1

The present invention relates to new and useful improvements in railway switches and more particularly to a novel paved track switch where an open switch is not permitted.

An important object of the invention is to provide a symmetrical switch tongue and connecting means therefor which may be interchangeably used for right or left hand switches in a right or left hand bed for a right or left hand turnout, whereby only one type of replacement parts need be carried in stock for repairs.

Another object is to generally improve the switch construction without sacrificing the required standards of strength and safety.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view;

Figure 2 is an enlarged fragmentary horizontal sectional view of the heel of the switch;

Figure 3 is an enlarged fragmentary top plan view of the toe of the switch tongue;

Figure 4 is a transverse sectional view taken on a line 4—4 of Figure 3;

Figure 5 is an enlarged fragmentary horizontal sectional view of the toe of the switch tongue and showing the connection for the connecting rod;

Figure 6 is a side elevational view of the switch tongue;

Figure 7 is a top plan view thereof;

Figure 8 is an enlarged fragmentary side elevational view of the guard rail showing the slot in which the connecting rod works;

Figure 9 is an enlarged transverse sectional view taken on a line 9—9 of Figure 1; and

Figures 10 and 11 are transverse sectional views taken respectively on the lines 10—10 and 11—11 of Figure 6.

Referring now to the drawings in detail, wherein for the purpose of illustration I have disclosed a preferred embodiment of my invention, the numeral 5 designates the outside stock rail of a railway switch construction and 6 the inside guard rail and between which the switch tongue 7 swings in the usual manner.

The tongue comprises a base flange 8, a web 9 and a head 10, the flange 8 tapering toward the toe 11 of the tongue from a point indicated at 12 adjacent its heel, the front end 13 of the flange ending rearwardly of toe 11. Web 9 is provided at each side with reinforcing bars 14

and 15 welded or otherwise suitably secured to the web between flange 8 and head 10; the bars 14 and 15 being rounded at their upper and lower edges to conformably fit under the head and on the flange of stock rail 5 and guard rail 6 as shown in Figure 4. The bars 14 and 15 are of uniform thickness and extend from a point indicated at 16 adjacent the heel of the tongue to the extremity of the toe.

Head 10 of tongue 7 tapers from a point indicated at 18 forwardly of the rear ends of bars 14 and 15 to the toe 11 so that at the toe of the tongue the head merges to the approximate width of web 9 and at the extremity of the toe the head 10 is beveled at each side to a point 19 for closely fitting in the angles 20 and 21 of outside stock rail 5 and inside guard rail 6, as shown in Figure 3.

Fish plates 22 and 23 are secured at the outside of stock rail 5 and guard rail 6 at the rail joints at the heel of tongue 7 by bolts 24 which also extend through filler blocks 25 and 26 which form fish plates at the inside of rails 5 and 6 as well as forming fish plates at the opposite sides of lead rail 27 leading rearwardly from tongue 7.

The filler block 25 tapers toward its front end, as shown in Figure 2 and filler blocks 25 and 26 are formed with extensions or tongues 28 and 29 at their front ends between which the heel portion 30 of web 9 of tongue 7 is loosely positioned and held therein by a pin 31 and with the heel portion of base flange 8 underlying the tongues 28 and 29. Tongue 28 is inclined toward outside stock rail 5 to enable switch tongue 7 to swing horizontally on pin 31 toward the stock rail and extension or tongue 29 is inclined a similar degree toward guard rail 6 to enable horizontal swinging movement of switch tongue 7 in that direction. This inclination of extensions 28 and 29 is identical to adapt the same to either a right or left hand turnout.

The web of guard rail 6 is formed with an opening 32 for the insertion of pin 31 and opening 32 is boxed on the outside, as indicated at 33.

The switch tongue 7 is swung from side to side by means of a connecting rod 34 to the end of which an internally threaded thimble 35 is welded and in which a bolt 36 is threaded and passing freely through an opening 37 in web 9 of the switch tongue to hold thimble 35 against the inner side of switch point 11, while the head 38 of the bolt is tightened against the outer side of the switch point. Head 38 is recessed in a square opening 39 in reinforcing bar 14.

The connecting rod 34 passes freely through a slot 40 in the web of guard rail 6 for operation by a suitable switch throw mechanism (not shown).

The outside stock rail 5 and guard rail 6 are reinforced at the end of the guard rail by a filler block 41 and both the stock rail 5 and guard rail 6 are provided with bracing webs 42 and 43, carried by base plates 44.

Filler plates 45 are suitably secured on base plates 44 under the toe of tongue 7 forwardly of the front end of base flange 8 to support the front end of the tongue.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A railway switch comprising a switch tongue including a base flange, a web and a head, said flange terminating rearwardly of the front end of the tongue and said head at the heel portion of the tongue corresponding in width to that of the head of a standard rail and tapering symmetrically toward the front end of the tongue from a point spaced forwardly of the rear end of the tongue to a width corresponding substantially to the width of the web, said head being beveled at opposite sides to a point at the tip of the tongue, and means pivotally connecting the rear end of the tongue to a lead rail.

2. A railway switch comprising a switch tongue including a base flange, a web and a head, said flange terminating rearwardly of the front end of the tongue and tapering toward the front end of the tongue from a point spaced forwardly from the rear end of the tongue and said head tapering toward the front end of the tongue to a width corresponding substantially to the width of the web, said head being beveled at opposite sides to a point at the tip of the tongue and tapered symmetrically to the front end of the tongue from a point spaced forwardly from the rear end of the tongue, longitudinal reinforcing bars secured to the sides of the web and extend-

ing from the tip of the tongue to a point rearwardly of the front terminus of the flange, and means pivotally connecting the rear end of the tongue to a lead rail.

3. A railway switch comprising a switch tongue including a base flange, a web and a head, said flange terminating rearwardly of the front end of the tongue and said head tapering toward the front end of the tongue to a width corresponding substantially to the width of the web, said head being beveled at opposite sides to a point at the tip of the tongue, longitudinal reinforcing bars secured to the sides of the web and extending from the tip of the tongue to a point rearwardly of the front terminus of the flange spaced forwardly of the rear end of the tongue, and rearwardly of the tapered portion of the head, and means pivotally connecting the rear end of the tongue to a lead rail.

4. In a railway switch, a switch tongue, and means connecting the rear end of the tongue to a lead rail for swinging movement of the tongue toward either an outside stock rail or an inside guard rail, said means comprising a filler block between the lead rail and the outside stock rail, a second filler block between the lead rail and the inside guard rail, a pair of spaced apart tongues projecting forwardly from said blocks and inclined uniformly in opposite directions from each other, and between which the rear end of the web of the switch tongue is loosely positioned, and means carried by said pair of spaced tongues connecting the rear end of the switch tongue thereto for swinging movement of the front end of the switch tongue toward either the stock or guard rail.

5. The combination of claim 4 wherein said switch tongue is symmetrical in shape for interchangeable use with either a right or left hand switch turnout.

EUGENE O. HUMPHREY.
